UNITED STATES PATENT OFFICE.

HARRY I. CLULEE, OF WALLINGFORD, CONNECTICUT, ASSIGNOR TO R. WALLACE & SONS MFG. CO., OF WALLINGFORD, CONNECTICUT, A CORPORATION.

METHOD OF FORMING HANDLES FOR METAL VESSELS.

Application filed March 18, 1926. Serial No. 95,656.

I do hereby declare the following, when taken in connection with the accompanying drawings and the characters of reference marked thereon, to be a full, clear, and exact 5 description of the invention, and which said drawings constitute part of this application, and represent, in—

Fig. 1, a plan view of a strip of metal, indicating a method of cutting blanks therefrom.

Fig. 2, a perspective view of a blank.

Fig. 3, a side view of the blank after it has been compressed edgewise.

Fig. 4, a sectional view on the line 4—4 15 of Fig. 3, the blank in its original form being indicated in broken lines.

Fig. 5, a side view of a finished handle.

Fig. 6, a plan view of a second form of handle constructed in accordance with this 20 invention.

This invention relates to improvement in method of forming handles for metal vessels and particularly metal articles for table service, such, for instance, as small pitchers, 25 sugar bowls, metal serving dishes, and similar articles. Handles for the purpose specified have been cast, but difficulty is always experienced in making perfect castings. Handles for this purpose have also been 30 formed from wire rods, but it is obvious that the variations in the form and design of the handles must necessarily be limited. The object of this invention is to form the handles from sheet-metal, and the invention consists in the method hereinafter described and 35 particularly recited in the claim.

In carrying out my invention, I strike a blank 10 from a strip 11 of sheet-metal of the required thickness. This blank has a 40 width greater than the thickness of the metal from which the blank is cut and contains the amount of metal necessary to form a handle of the desired shape. For instance, the ends are enlarged to provide metal for 45 the miter ends 12 and 13 of the finished handle. The blank is also widened at a

point as 14 to provide metal for an embossed ornamentation or tip 15.

The blank thus cut and as shown in Fig. 2 of the drawings, is then placed in a press 50 and compressed edgewise, producing a handle-blank, as shown in Fig. 3 of the drawings, of the desired cross-section and with miters 12 and 13 of a size suitable for the purpose for which the handle is to be used 55 and, at the same time, the tip 15 is formed on the blank. The blank thus partly formed is then bent in a plane parallel with the width of the blank in its original form by suitable means into the desired form, as indicated in Fig. 5 of the drawings, which 60 brings the miter-faces 12 and 13 into proper alignment for attachment to a vessel.

Some handles are in the form of a U-shaped loop, as indicated in Fig. 6 of the 65 drawings, and these handles can be formed in the same way, it only being essential that the blank, as initially cut, shall have sufficient metal at desired points to form the completed article when the blank is struck 70 edgewise.

With this method of forming handles, the loss by imperfect casting is greatly reduced, the ornamental tip and miter faces can be 75 much more pronounced than would be possible in handles formed from wire, and the saving of finishing handles struck from sheet-metal over handles formed from cast-metal is accomplished.

I claim:

A method of forming metal handles, consisting in striking a blank from a sheet of metal of the desired thickness and of a width greater than the thickness, compressing the blank edgewise and then bending the partly 85 developed blank in a plane parallel with the width of the blank in its original form to the desired shape.

In testimony whereof, I have signed this specification.

HARRY I. CLULEE.
